CLAIM

The ornamental design for a pack station, as shown and described.

DESCRIPTION

FIG. 1 is a perspective view of a pack station showing our new design;

FIG. 2 is a front view thereof;

FIG. 3 is a rights side view thereof, the left side view being a mirror image; and,

FIG. 4 is a top view thereof.

The broken lines shown in the drawings are included for purposes of illustrating portions of the pack station and form no part of the claimed design.

1 Claim, 4 Drawing Sheets(56)
